DESIGN FOR AN ELECTRIC SWITCH

Robert M. Lynn, Pasadena, Calif.

Application February 2, 1944, Serial No. 112,409

Term of patent 7 years

(Cl. D26—13)

To all whom it may concern:

Be it known that I, Robert M. Lynn, residing at Pasadena, in the county of Los Angeles and State of California, have invented a new, original, and ornamental Design for an Electric Switch, of which the following is a specification, reference being had to the accompanying drawing, forming a part thereof.

Fig. 1 is a top plan view of an electric switch showing my new design.

Fig. 2 is a side elevational view.

Fig. 3 is a view looking against the underside of the switch.

Fig. 4 is a front elevational view, and
Fig. 5 is a rear elevational view.

I claim:

The ornamental design for an electric switch,
as shown.

ROBERT M. LYNN.
